Primary Examiner — Adir Aronovich(74) Attorney, Agent, or Firm — Michael Best & Friedrich LLP(57) CLAIM

The ornamental design for a camera, as shown.

DESCRIPTION

FIG. 1 is a front, top, right perspective view of a camera showing my new design;

FIG. 2 is a rear perspective view thereof;

FIG. 3 is a front elevational thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate unclaimed portions of the camera and form no part of the claimed invention.
